UNITED STATES PATENT OFFICE.

FRANCIS M. COMSTOCK, OF TOPEKA, KANSAS, ASSIGNOR TO THE COMSTOCK MOTOR COMPANY, OF SAME PLACE.

DESIGN FOR A CASING FOR FLUID-PRESSURE ENGINES.

SPECIFICATION forming part of Design No. 26,621, dated February 9, 1897.

Application filed January 4, 1897. Serial No. 617,963. Term of patent 14 years.

To all whom it may concern:

Be it known that I, FRANCIS M. COMSTOCK, a citizen of the United States, residing at Topeka, in the county of Shawnee and State 5 of Kansas, have invented and produced a new and original Design in Casings for Fluid-Pressure Engines, reference being had to the accompanying drawings, forming a part hereof.

- 10 In the accompanying drawings, Figure 1 is a perspective view of my design, looking at it from the top; and Fig. 2, a perspective view, looking at it from the bottom.
- 15 The leading feature of my design consists in a substantially heart-shaped portion provided with a projection at one side thereof.

A is the heart-shaped portion, and B the projection at one side thereof, the whole presenting to the eye a harmonious and ornate figure, as shown in the accompanying drawings. 20

I claim—

The design for a casing for fluid-pressure engines substantially as herein shown and described.

FRANCIS M. COMSTOCK.
